UNITED STATES PATENT OFFICE

2,118,193

BUILDING CONSTRUCTION

Heinrich Griesel, Berlin, Germany

Application February 18, 1935, Serial No. 7,135
In Germany August 18, 1933

14 Claims. (Cl. 72—65)

My invention relates to building constructions. More particularly, it relates to constructions comprising a pair of flanged supports, normally I-iron girders, abutment members or stones supported on the flanges of the supports, load-bearing cover plates inserted between the abutment members and acting thereon like a vault through diagonal surfaces on the members and the plates, and closing means below the plates which are fixed by the abutment members. Certain of the aforementioned features in building construction are described and claimed in my United States Patent No. 2,002,347, which issued May 21, 1935, and it is an object of this invention to provide an improved building construction of that character.

To this end, I provide slots in the lower ends of the abutment members which bear on the lower flanges of the I-iron girders, and in the slots I insert the ends of battens which also bear on the lower flanges and are fixed by the abutment members. The battens are equipped with means for holding a lower covering layer. Preferably, the holding means are inserted in the battens while the battens are made, and the means are wire loops with projecting ends engaging in the layer which may be plaster or insulating material.

By inserting the ends of the battens in slots of the abutment members, I reduce the overall height of the construction, and, since the ends of the battens are fixed by the abutment members, the battens are comparatively thin and light even for large spans.

The battens are preferably made of fireproof material, and the holding means which, as mentioned, are preferably inserted while the battens are made, may be wire loops, as mentioned, or they may be of hoop iron, or they may be pointed like nails to facilitate the penetration of the layer of plaster or the like. The layer itself is fixed by bending or winding of the projecting ends of wire loops or the like, or by wedges or pins inserted in the projecting ends of hoop-iron members. The ends of the members may also be bent or wound, and then the said wedges or pins may be inserted.

Instead of a single layer of plaster or the like which is attached to the battens by their holding means, I may attach a plurality of layers, for instance, an insulating layer and wire netting for plaster, placed directly one upon the other or spaced apart at any desired distance, without reducing the strength of the structure the fixed battens make up together with the other parts of the construction.

In the manner described, I may also build in

over and/or between such layers which are made in succession, insertions in the shape of individual rods, netting or the like, for bracing the layers, or I may arrange pipes or cables built in similarly.

Obviously, the distance between the two flanged supports or girders which is to be spanned by the aforesaid members, is not the same for various buildings, ceilings, etc. This involves the necessity of dimensioning the covering plates and battens for the span of each individual structure. This is not very important with respect to the battens but the difficulty is to keep in stock so many cover plates of various sizes.

It is another object of my invention to overcome this drawback. To this end, I standardize the elements, i. e., the abutment members and the cover plates. The various distances between girders are made up for by suitably varying the thickness of the abutment members. With such abutment members, it is only necessary to keep in stock a few sizes of cover plates. By way of example, the thicknesses of the standardized abutment members may vary 2 inches, so that the spans vary 4 inches, and so the sizes of the cover plates to be kept in stock differ for 4 in. from each other.

The joints between the individual parts of my construction are filled in with mortar.

My invention also relates to the abutment members or stones, and it is still another object of my invention to improve such members by modifying in various ways.

To this end, I provide, in an abutment member having a diagonal surface at its upper end for the reception of the corresponding diagonal surface of a cover plate, and a downwardly inclined face below the diagonal surface; a horizontal face at the upper end of the diagonal surface, and not less than one recess in the face of the abutment member which is opposite the diagonal surface, for the reception of a flange, or the flanges, of a girder.

I may also make the abutment surface so high that the aforesaid horizontal face beyond which the cover plate extends and on which it is supported, is at a higher level than the upper flange of the girder, while, on the other hand, I may make the downwardly inclined face so long that the lower end of the abutment member engages about the lower flange of the girder.

By so selecting the size of the abutment members that they project beyond the girder flanges, the most favorable proportion of the masses of the abutment members and the cover plates inserted between them, may be obtained.

Abutment members according to my invention, as described above, are preferably used for the described ceiling and vault constructions, but may also be used for ceiling and other structures 5 of other types, in particular for such structures in which the aforesaid battens and the layer, or layers, which they support, are dispensed with, and the lower faces of the abutment members and the cover plates inserted between each two 10 members, make up together a vault or arch, or they may be used for ceiling and other structures in which the cover plates are hollow and the lower ends of the abutment members themselves make up the lower end of the construction.

15 In the accompanying drawings, various constructions and abutment members and cover plates embodying my invention are illustrated by way of example.

In the drawings:

20 Fig. 1 is a cross section of a construction comprising a solid cover plate and slotted abutment members,

25 Fig. 2 is a cross section showing one half of a construction comprising a trough-shaped cover plate and abutment members without slots,

Fig. 3 is an elevation showing one of the slotted abutment members in Fig. 1, partly broken away and viewed in the direction of arrow III, Fig. 1.

30 Figs. 4a to 4e are sections on the line IV—IV in Fig. 1 and showing modifications of the connection between the covering layer and a batten,

35 Figs. 5a and 5b illustrate, by way of comparison, standardized abutment members and cover plates according to Figs. 1 and 2, respectively,

Fig. 6 is an elevation of an abutment member 35 having a horizontal face at the upper end of its diagonal surface, and a recess for the reception of the upper girder flange,

Fig. 7 is an elevation of an abutment member 40 which is similar to the one illustrated in Fig. 6, but divided at the recess,

Fig. 8 is an end elevation, and

Fig. 9 is an elevation, viewed from the left in Fig. 8, of a hollow abutment member whose diagonal face is grooved and whose ends are equipped with a projection and a recess, respectively, for connecting it to other members,

Fig. 10 is an elevation of an abutment member 50 with two recesses, one for the upper, and the other for the lower flange of the girder,

Fig. 11 is a cross section showing one half of a construction which is similar to the one illustrated in Fig. 1, but whose abutment members are extended beyond the upper flange of the 55 girder, and stepped instead of being recessed, for the upper flange, and

Fig. 12 is a cross section of the vault-like construction referred to in which the abutment members illustrated in Fig. 6 are used.

60 Referring now to the drawings, and first to Figs. 1 and 3, the flanged supports are shown as the I-iron girders of a ceiling at 1. 2 is one of the battens referred to which are placed on the lower flanges of the girders with their stepped ends. 3 are the two abutment members which are allotted to the batten 2, and are slotted in their lower ends at 4, Fig. 3, for the reception of the corresponding batten end. The abutment members are placed against the inner sides of the girder webs between their upper and lower flanges, as shown in Fig. 1, and are held in position by their engagement with the battens which make a tight fit in the slot 4. At the same time, the battens 2 are firmly seated and fixed on the 70 lower flanges of girders 1, and thrust is exerted 75

against the upper portion of the girders 1. The abutment members each have a vertical outer face with which they bear against the web and flanges of the girders 1 at their inner sides, as shown in Fig. 1, a diagonal surface 25 at their inner side which extends as far as the upper end of the abutment member, and a downwardly inclined face 27 which extends from the lower end of the diagonal surface 25 as far as the lower end of the abutment member, and is broken by the slot 4. When the abutment members have been placed in position as described, a solid cover plate 5 having diagonal surfaces 6, is placed between the diagonal surfaces 25 of the abutment members and exerts thrust on them by its vault-like action, at the same time fixing the battens 2 by means of the slots 4 in the abutment members, as described. Thrust is exerted against the upper portions of the girders 1, as mentioned. The top of the cover plate 5 is flat but its base is arched, so that there is a space between the battens 2 and the cover plates 5.

Steel members 24 are preferably inserted in the cover plates 5, and connected to corresponding steel members of the adjacent cover plates, as described in my said patent, so that a continuous ceiling or other construction is obtained which is strong against tension and thrust forces. The ends of the steel members 24 which are at the sides of the construction, are anchored in the 30 walls of the building of which the construction forms part.

The construction has two covering layers 9 and 10 at its lower end. The upper layer 9 may be a wire netting or the like for supporting the 35 plaster, or an insulating layer, and the other layer is of plaster.

The means for connecting the layers 9, 10 to the battens 2 will now be described with reference to Figs. 4a to 4e. The battens 2 are supposed to 40 be made of concrete, with a pair of parallel steel insertions 2'.

Referring now to Fig. 4a, loops 7, of wire, hoop iron, or the like are inserted in the battens with their lower ends 8 projecting from the lower face of the batten for some distance, as shown in dotted lines. When the battens have been inserted between the girders 1, as described, and the construction has been assembled, the layer 9 is placed on the projecting ends of the loops which 50 are preferably pointed to facilitate penetration through the layer, as shown in Figs. 4d and 4e for a modified design, and the ends are bent over, as shown in full lines, whereupon the plaster 10 is applied.

55 Referring now to Fig. 4b, the batten 2 is equipped as described but the two layers 9 and 10 are spaced apart, and spacing members 11 are inserted between the two layers, and held by the projecting ends 8 of the loops 7. In this manner an insulating cavity is obtained between the layers 9 and 10. Instead of the spacing members 11, steel members for wire netting may be inserted for bracing the intermediate layer 9 and/or the plaster layer 10.

60 Referring now to Fig. 4c, the spacing members 11 are provided as described but cables 12 or pipes 12' may be inserted between the layers together with the spacing members 11, or the spacing members may be replaced altogether by pipes 70 or cables.

Referring now to Figs. 4d and 4e, the projecting end 83 of a flat member 71 which is pointed, has a slot for the insertion of a wedge or pin 7a.

As mentioned, the ends of the loops are prefer- 75

ably pointed, and this is shown in dotted lines in Figs. 4d and 4e. When the layer 9, or any other layer, has been fixed by the wedge 1a, the pointed ends of the loops 7 are preferably turned down 5 on the wedges 1a, as shown in Fig. 4e.

Referring now to Fig. 2, the girders 1 and the covering layers 9 and 10 are provided as described, and the abutment members 3 are placed between the flanges of the girders, as also described, but 10 in this case the lower ends of the abutment members are without slots, and are extended beyond the lower flanges of the girders. The face 27 is dispensed with, the diagonal surface 25 extending throughout the height of the abutment members 3. The cover plate 5 which has diagonal surfaces 6, as described, is trough-shaped and extends in downward direction as far as the lower ends of the abutment members 3, so that the lower face of the covering plate supports the 15 layers 9 and 10, or only the plaster layer 10, and the battens 2 are dispensed with. The cavity of the trough-shaped cover plate 5 may be filled in with any suitable material such as slag, sand, or the like, as indicated at 13, and a wooden floor 20 25 may be placed on the filler.

Referring now to Figs. 5a and 5b, these are reproductions of Figs. 1 and 2, respectively, but show an example for the standardization referred to. The thickness of the abutment members 3 illustrated in Figs. 1 and 2 is indicated in dotted lines, and the members 3' are thicker than the members in Figs. 1 and 2. For example, the distance of the full and dotted lines may be 2 in., as explained above.

35 Various types of abutment members will now be described with reference to Figs. 6 to 11.

Referring first to Fig. 6, this abutment member 3, which may be partly hollow as shown at 32, has the diagonal surface 25, the inclined face 27 40 and the horizontal face 28, as described, but the inclined face 27 is not as steep as in Fig. 1 because it is intended to form part of a vault, as will be described with reference to Fig. 12. The outer face of the abutment member is recessed at 29 for the reception of the upper girder flange. By means of this recess, the abutment members are threaded on the girders 1 as shown in Fig. 12, and the upper portion 21 of each member bears 45 on the upper flange from above and presents a horizontal face to the cover plate 5 whose diagonal surfaces 6 engage the mating surfaces 25 of the abutment members. It will appear that abutment members, even if large, are firmly seated between the girder flanges, without being 50 supported by lagging, before the covering plates 5 are inserted. If desired, this member may be solid.

Referring to Fig. 7, this abutment member is similar to the one illustrated in Fig. 6 as to its 55 outline, but is divided into a lower portion 30 and an upper portion 31. The recess 29 is in the upper portion as shown in full lines, but it may also be in the lower portion, as shown in dotted lines.

65 Referring to Figs. 8 and 9, this abutment member is also similar to the one in Fig. 6, and undivided. It has two cavities 32, as seen in Fig. 9, and its diagonal surface is grooved at 26 so that the mortar takes a better hold thereon. To place 70 the several abutment members in as close a vicinity to each other as is practicable, the abutments are notched at 33 in one of their end faces while the other end face has a rib 34 to engage in the notch 33 of the adjacent member. This 75 design is not limited to the type of abutment

member illustrated in Figs. 8 and 9 but may be adapted to any member, if desired.

Referring to Fig. 10, this abutment member which may be hollow as indicated at 32, has a recess 22 for the lower girder flange, in addition 5 to the recess 29 for the upper flange, as described. It will appear that the girders 1 are protected against fire from below by the lower portion or lug 23 of the abutment member 3.

Referring now to Fig. 11, this abutment member is similar to the one illustrated in Fig. 1 but has an upper extension beyond the upper flange of the girder at 15. This extension 15 places the cover plate 5 at a higher level and increases the height of the space between its arched bottom 15 and the top of battens 2. The layers 9 and 10 are provided as in Fig. 1.

Referring now to Fig. 12, the abutment members of Fig. 6 are used in this ceiling structure. The members are threaded on the girders 1, with 20 the upper girder flanges engaging in recesses 29, as described. The load-bearing cover plates 5 are inserted between the diagonal surfaces 25 of the members with their diagonal faces 6, and make up vaults with the inclined faces 27 of the 25 members. The steel members 24 are connected where they project from the sides of the cover plates 5, as and for the purpose specified.

By way of example, the ceiling construction in Fig. 12 has been shown as arranged below an 30 existing ceiling, or floor, 35, with I-iron girders 36. The ceiling below is provided as a stand-by in case the ceiling above breaks down as may occur if a building falls down. If the upper portions 21 of the members project beyond the upper 35 girder flanges, as in the example illustrated, the clearance between the two ceilings can be made quite low and may be filled in, so that both ceilings bear load together.

Obviously, I am not limited to the use of my 40 abutment members for the constructions shown in Figs. 1, 2, 11, and 12.

I claim:

1. A building construction comprising a pair of flanged supports, an abutment member bearing 45 on a flange of each support with its lower end and having a slot in such lower end, and a diagonal surface at its upper end; a load-bearing cover plate inserted between, and supported by, the diagonal surfaces of said abutment members 50 by corresponding diagonal surfaces and exerting a vault-like side thrust against said abutment members, a batten inserted in a slot of each abutment member supported by the flanges of the supports said abutment members bear on, and fixed by said abutment members, a lower covering layer, and means in said batten for holding 55 said layer.

2. A building construction comprising a pair of flanged supports, an abutment member bearing 60 on a flange of each support with its lower end and having a slot in such lower end, and a diagonal surface at its upper end; a load-bearing cover plate inserted between, and supported by, the diagonal surfaces of said abutment members 65 by corresponding diagonal surfaces and exerting a vault-like side thrust against said abutment members, a batten inserted in a slot of each abutment member, supported by the flanges of the supports said abutment members bear on, and 70 fixed by said abutment members, a lower covering layer, a member inserted in said batten with its slotted end projecting therefrom, and a transverse member inserted in the slot of the member for holding said layer.

3. A building construction comprising a pair of flanged supports, an abutment member bearing on a flange of each support with its lower end and having a slot in such lower end, and a diagonal surface at its upper end; a load-bearing cover plate inserted between, and supported by, the diagonal surfaces of said abutment members by corresponding diagonal surfaces and exerting a vault-like side thrust against said abutment members, a batten inserted in a slot of each abutment member, supported by the flanges of the supports said abutment members bear on, and fixed by said abutment members, a lower covering layer, means supported by said batten for holding said layer, and an intermediate layer between said batten and said lower covering layer.
4. A building construction comprising a pair of flanged supports, an abutment member bearing on a flange of each support with its lower end, and having a slot in such lower end, and a diagonal surface at its upper end; a load-bearing cover plate inserted between, and supported by, the diagonal surfaces of said abutment members by corresponding diagonal surfaces and exerting a vault-like side thrust against said abutment members, a batten inserted in a slot of each abutment member, supported by the flanges of the supports said abutment members bear on, and fixed by said abutment members, a lower covering layer, means supported by said batten for holding said layer, an intermediate layer between said batten and said lower covering layer which intermediate layer is spaced from said covering layer, and spacing members inserted between said layers.
5. A building construction comprising a pair of flanged supports, an abutment member bearing on a flange of each support with its lower end, and having a slot in such lower end, and a diagonal surface at its upper end; a load-bearing cover plate inserted between, and supported by, the diagonal surfaces of said abutment members by corresponding diagonal surfaces and exerting a vault-like side thrust against said abutment members, a batten inserted in a slot of each abutment member, supported by the flanges of the supports said abutment members bear on, and fixed by said abutment members, a lower covering layer, means supported by said batten for holding said layer, an intermediate layer between said batten and said lower covering layer which intermediate layer is spaced from said covering layer, and pipes inserted between said layers for spacing them.
6. A building construction comprising a pair of flanged supports, an abutment member bearing on a flange of each support with its lower end, and having a slot in such lower end, and a diagonal surface at its upper end; a load-bearing cover plate inserted between, and supported by, the diagonal surfaces of said abutment members by corresponding diagonal surfaces and exerting a vault-like side thrust against said abutment members, a batten inserted in a slot of each abutment member, supported by the flanges of the supports said abutment members bear on, and fixed by said abutment members, a lower covering layer, means supported by said batten for holding said layer, an intermediate layer between said batten and said lower covering layer which intermediate layer is spaced from said covering layer, and spacing members inserted between said layers and fixed by said layer-holding means.

7. Covering plates and abutment members for building constructions in which said abutment members bear on flanges of supports forming part of said construction and have diagonal surfaces at their upper ends for supporting load-bearing cover plates with mating diagonal surfaces, said covering plates and abutment members being provided in sets of different widths each movement of which is in multiples of $\frac{1}{2}$ inch, thus being standardized for various distances between said supports.

8. A floor-and-ceiling construction comprising two beams, load carrying covering plates arranged between the two beams, abutment blocks interpositioned, the plates being supported as in a vaulted construction by means of oblique surfaces engaging corresponding oblique surfaces on the abutment blocks, the plates being trough-shaped in such manner that the horizontal lower surface of each covering plate lies approximately at the level of the lower flange of the beam, the layers constituting the lowermost elements of the construction being secured to this lower surface.

9. A floor-and-ceiling construction according to claim 4, in which the load carrying covering plates have lateral extensions which rest on the upper flanges of the beams, and iron reinforcements projecting from these extensions, said reinforcements being connected with the reinforcements of adjacent structural elements.

10. In a building construction in which there is a flanged support and an abutment member adapted to be placed on the flange of said support with its lower end, and in which said abutment member has a slot in such lower end and a diagonal surface at its upper end; an inclined face extending from the lower end of said diagonal surface as far as the lower end of said abutment member.

11. In a building construction, the combination which comprises a flanged support, and an abutment member, said abutment member having a lower end adapted to be placed upon a flange of the support, a diagonal surface, and a horizontal face adjacent the upper end of the diagonal surface, said horizontal face extending beyond the upper end of the support.

12. In a building construction, the combination which comprises a flanged support, and an abutment member, said abutment member having a lower end adapted to be placed upon a flange of the support, a diagonal surface, a horizontal face at the upper end of the diagonal surface, and a lug extending under the lower flange of the support.

13. In a building construction, the combination which comprises a flanged support and an abutment member, said abutment member having a lower end adapted to be placed upon a flange of the support, a diagonal grooved surface, and a horizontal face at the upper end of the diagonal surface.

14. In a building construction, the combination which comprises a flanged support, and an abutment member, said abutment member having a lower end adapted to be placed upon a flange of the support, a diagonal surface, and a horizontal face on the upper end of the diagonal surface, and means at the sides of the abutment member for connecting it to adjacent abutment members.
